Alois P. Prendergast Inventor

By Mauro, Cameron, Lewis & Kirkham

Attorney

UNITED STATES PATENT OFFICE.

ALOIS P. PRENDERGAST, OF DALLAS, TEXAS.

GAUGE COCK.

Application filed April 4, 1921. Serial No. 458,403.

To all whom it may concern:

Be it known that I, ALOIS P. PRENDERGAST, a citizen of the United States, and a resident of Dallas, Texas, have invented new and 5 useful Improvements in Gauge Cocks, which invention is fully set forth in the following specification.

This invention relates to improvements in gauge-cocks, and has for its object to simplify the construction and reduce the cost of manufacture of the gauge-cock disclosed in my Patent No. 843,842, granted February 12, 1907. As gauge-cocks are in constant use to test or gauge the height of water in the 15 boiler, the same being operated many times daily, there is a resultant wear upon the valve and valve seat which necessitates frequent repairs or replacement of the parts. One of the objects of the present invention 20 is to provide means whereby a removable and reversible valve seat may be employed to the end that, when said seat becomes worn, it may be reversed. Moreover, if the valve itself becomes worn or injured, a new valve 25 may be readily substituted, and a further object is to accomplish the construction of such a valve in such a manner that the separation of the parts for the removal or reversal of the valve, and the substitution of 30 a new valve is desired, may be accomplished in the shortest possible time.

With these objects in view, the invention consists in the construction and combination of elements hereinafter described and then 35 more specifically pointed out in the claim.

The figure of the drawing constituting a part of this specification is a longitudinal central section through an improved valve of my construction, and in which 1 is the valve 40 casing, 2 is a tubular extension thereof provided with screw-threads 3 for connecting the same with the boiler, said tubular extension being in communication with the valve casing. Said casing is provided with an 45 annular shoulder 4 upon which rests a reversible and removable valve seat 5, which valve seat is in the form of a ring having flat sides and a suitably formed seating for the valve in the axial opening therethrough, 50 there being two similar seats one on either side. A nut 6 is provided with an inwardly extending shank 7 screw-threaded into the valve casing 1 and engaging the valve seat 5 and holding it in place. Said shank 7 is

provided with an axial chamber 8 and, if 55 desired, it may be, and preferably is, provided with a shouldered part 9 to engage the valve seat 5, though it will be manifest that, if desired, the valve seat may be of approximately the same diameter as the interior of the valve casing and simply be engaged by the end of the shank 7. Within the chamber there is provided an annular channel 10 surrounding the shank 7, which latter is provided with radial openings 11 60 whereby the interior of the chamber 8 is in open communication with the annular channel 10, the latter communicating with the discharge nozzle 12.

The nut 6 is interiorly screw-threaded and 70 the valve stem 13 has exterior screw-threads engaging the same, said stem carrying the valve 14 of any suitable or desired construction on its inner end to engage the valve seat 5. Preferably, this valve 14 is removably secured to the valve stem, as by means 75 of a shank 15 extending axially into said valve stem.

The nut 6 is also provided with an outwardly extending shank 16, screw-threaded 80 on its exterior, and a cap 17 screw-threaded onto said shank serves to compress the usual or any suitable packing 18 against the outward end of the shank 16 and around the valve stem 13. The valve stem 13 is provided with the usual or any suitable operating-handle 19.

When it is desired to reverse the valve seat 5, or to remove it and replace a new one, all 90 that is necessary to do is to unscrew the nut 6. The valve seat may then be readily removed and reversed, or a new valve seat placed in position, and by screwing the nut 6 again into the valve casing the valve is 95 ready for operation.

It will be perceived that I have provided a valve of great simplicity of construction, which may be disassembled and reassembled in the shortest possible time for repairs, and in which the parts are all readily machined 100 when constructing the device.

What is claimed is:—

In a gauge-cock, the combination with a casing having one end exteriorly threaded and its opposite end enlarged to form an 105 interiorly threaded chamber, of a removable valve and a reversible and removable valve-seat, both within the casing, a nut having a

chambered shank screw-threaded into said chamber, said shank being provided with radial openings in communication with an annular channel formed in said chamber, a 5 valve-stem screw-threaded into said nut and carrying the shank of said valve in the inner end thereof, and a discharge nozzle formed

on the enlarged end of said casing and in open communication with the threaded chamber thereof.

In testimony whereof I have signed this specification.

ALOIS P. PRENDERGAST.
